UNITED STATES PATENT OFFICE.

DAVID LOW AND ALBERT R. THOMPSON, OF SAN JOSE, CALIFORNIA; SAID THOMPSON
ASSIGNOR TO SAID LOW.

FEEDER ESPECIALLY ADAPTED FOR ASPARAGUS-HANDLING MACHINES.

1,299,198.

Specification of Letters Patent.

Patented Apr. 1, 1919.

Application filed November 26, 1918. Serial No. 264,271.

To all whom it may concern:

Be it known that we, DAVID Low and ALBERT R. THOMPSON, citizens of the United States, residing at San Jose, in the county of Santa Clara and State of California, have invented certain new and useful Improvements in Feeders Especially Adapted for Asparagus-Handling Machines, of which the following is a specification.

10 Our invention relates, in general, to the class of feeders by which material is supplied to machines to handle it; and, in particular, it relates to a feeder which is especially adapted to supply elongated vegetables, such, for example, as asparagus, to machines which grade the stalks in respect to thickness and which reduce them to uniform length suitable for packing in tins.

While our invention is applicable to any 20 material composed of individuals which, for effective handling in the machine supplied, require to be spread out and introduced singly, it is particularly useful for feeding asparagus; and in this connection we shall describe it, though it is to be understood that we do not confine ourselves to this special use.

In the art of packing or canning asparagus, the preliminary essentials are grading 30 and uniform length, as we have in previous patents, namely No. 1,257,719, Feb. 26, 1918, and No. 1,282,250, Oct. 22, 1918, fully explained.

To attain these essentials with efficiency 35 the important factor is the maintenance throughout the entire operation of the uniform relation of individual shoots or stalks with respect to butts and tips, that is to say, the butts must lie all in the same direction. 40 This is found best accomplished by feeding each shoot singly in its own individual pocket to the machine; and this, in turn, requires personal care to see that each shoot is properly and singly disposed so that the material will reach the machine as individuals and all in uniform relation with respect to butts and tips.

The personal care thus imposed upon the operator, necessarily limits the capacity of 50 the machine, for it requires both time and labor to separate the shoots and supply them singly and in proper relation to the individual pockets of the inleading feed-belt of the machine.

55 It is the object of our present invention to

effect a saving in this regard by providing for the automatic spreading and segregation of the shoots and their delivery singly to the feed pockets of the machine.

To this end our invention consists in the novel feeder which we shall now fully describe by reference to the accompanying drawings in which,

Figure 1 is a plan view of our feeder.

Fig. 2 is a vertical longitudinal section on the line 2—2 of Fig. 1.

Fig. 3 is a cross-section on the line 3—3 of Fig. 1.

We have not deemed it necessary to illustrate the handling machine, which forms no part of our present invention though for this purpose, if desired, reference may be had to our previous patents above mentioned, and particularly to the later one, of which the belt 1 with its transverse pockets 2, is the in-leading feed belt.

In advance of this belt is the frame 3 of our present feeder.

In this frame is mounted a cross shaft 4 which carries a line of spreading members, here shown in the form of teeth 5 projecting from a hub 6, upon which hub are mounted the parallel carriers 7, which, in practice, are round belts. The other end of these belts are mounted upon a terminal roll 8.

Upon the hub 6 are mounted a second series of parallel carrier belts 9, the other ends of which are trained over a terminal roll 10, which latter is relatively small, so that the belts 9 may lie in close proximity to the main feed belt 1, and be adapted, without loss of space or danger of displacement to deliver the asparagus shoots into the pockets 2 of said feed belt, as best shown in Fig. 2. A frictionally driven brush 19, at this point serves to guide and hold each shoot to and in its pocket.

Mounted in the frame 3 are other cross-shafts 11, in any suitable number. Upon these cross-shafts are the successive lines of spreaders or teeth 12, projecting from hubs 13, upon which the carrier belts 9 rest so that the teeth 12 rise above said belts.

Both sets of carrier belts 7 and 9 and the spreader teeth 5 are driven from the hub 6 mounted on the cross shaft 4 the latter being driven through its gear 14 from a pinion 15 on a side shaft 16. The series or lines of teeth 12 are all driven at a higher rate of speed than that at which the belts are

driven; and, moreover, the rate of speed of each line of teeth 12 is different, being so regulated that the line of teeth 12 immediately following the line of teeth 5 is driven 5 at an increased speed as compared with the speed of the teeth 5, and the next line of teeth 12 is driven at an increased speed over the speed of the first line of teeth 12 and so forth to the end line of teeth 12, nearest the 10 pocket feed belt 1, which said end line has the highest speed.

Any suitable mechanism may be employed to differentiate the speed as described. For illustration we have shown a side-shaft 20 as 15 carrying a series of pinions 17 meshing with gears 18 of successively decreasing diameter on the ends of the cross shafts 11. The shaft 20 may be driven by the shaft 16, through gearing 21.

20 In practice we have found it desirable to make the initial line of teeth 5 larger than the succeeding line of teeth 12.

The operation of the feeder is as follows:

The asparagus shoots, supplied in mass 25 crosswise on the traveling carrier-belts 7 arrive more or less bunched at the line of teeth 5 and are picked up and carried over by said teeth and in this operation are partly separated or spread out, the relatively large size of said teeth acting favorably in this regard.

Somewhat separated the shoots are delivered upon the traveling carrier belts 9, and when they arrive at the first line of 35 teeth 12 they are again picked up and carried over, and in this operation, on account of the increased speed of said line of teeth, a further separation or spreading of the shoots is effected.

40 Arriving at the next line of teeth 12 which is rotating at an increased speed a still further spacing or spreading of individual shoots is effected. This operation is continued, until at the last line of teeth 12, 45 which is rotating at highest speed, the shoots are fully separated or spread out into individuals, and are delivered separately into successive pockets of the feed belt 1.

The increased speed of all the lines of 50 teeth 12 over the speed of the carrier belts insures against any piling up or crowding at said lines, and the successively increasing speeds of said lines segregate the shoots into individuals.

55 We claim:

1. A feeder for the described purpose comprising a traveling carrier on which the material rests and by which it is advanced; a series of cross-lines of rotating spreaders 60 disposed to act upon the advancing material on the carrier to separate its component parts; and means for imparting to successive-lines of spreaders an increased speed of rotation, whereby the separation of the advancing material is increasingly effected. 65

2. A feeder for the described purpose comprising a traveling carrier; a series of cross-lines of spreaders disposed to act upon the material on the carrier to separate its component parts, said lines of spreaders rotating at a higher rate of speed than the travel of the carrier; and means for imparting to successive lines of spreaders an increased speed of rotation whereby the separation of the material is increasingly effected. 75

3. A feeder for the described purpose comprising a series of parallel traveling carriers, and a series of cross lines of spreaders rising between the carriers and rotating in planes parallel with the direction of travel 80 of said carriers, said spreaders having a higher rate of speed than said carriers.

4. A feeder for the described purpose comprising a series of parallel traveling carriers on which the material rests and by 85 which it is advanced, and a series of cross lines of spreaders rising between the carriers and rotating in planes parallel with the direction of travel of said carriers, said spreaders acting upon the advancing material on the carriers to separate its component parts and each successive line of spreaders having a greater speed than that of the preceding line, whereby the separation of the advancing material is increasingly effected. 95

5. A feeder for the described purpose comprising a series of parallel traveling carriers, and a series of cross lines of spreaders rising between the carriers and rotating in 100 planes parallel with the direction of travel of said carriers, said spreaders having a higher rate of speed than said carriers, and each successive line of spreaders having a greater speed than that of the preceding line. 105

6. A feeder for the described purpose comprising a series of parallel traveling carriers; a cross line of spreaders rising between and rotating at the same rate of speed as the carriers, in planes parallel with their 110 direction of travel; and a succeeding series of cross lines of spreaders rising between and rotating at rates of speed higher than the rate of travel of the carriers and in planes parallel with their direction of travel, 115 each successive line of said series of spreaders having a greater speed than that of the preceding line.

7. A feeder for the described purpose comprising a first series of parallel traveling carriers; a cross-shaft; a line of spreaders carried by said shaft, said spreaders rising between said carriers and having a hub upon which the carriers are mounted and by which they are driven; a second series of parallel 120 traveling carriers, mounted upon and driven by the hub of the said spreaders; a series of cross shafts, each carrying a line of spreaders rising between said second carriers and having hubs upon which said carriers are 125 130

guided; and means for driving each succeeding cross shaft at relatively higher speed than that of the preceding cross shaft.

8. A feeder for the described purpose comprising a first series of parallel traveling carriers; a cross-shaft; a line of spreaders carried by said shaft, said spreaders rising between said carriers and having a hub upon which the carriers are mounted and by which they are driven; a second series of parallel traveling carriers, mounted upon and driven by the hub of the said spreaders; a series of cross-shafts, each carrying a line of spreaders rising between said second carriers and

having hubs upon which said carriers are 15 guided; and means for driving each succeeding cross-shaft at relatively higher speed than that of the preceding cross-shaft and all at a speed greater than the rate of travel of said second series of carriers.

20 In testimony whereof we have signed our names to this specification in the presence of two subscribing witnesses.
